N. D. CRAWFORD,
APPARATUS FOR MANUFACTURING ARTICLES FROM LIQUID MATERIAL.
APPLICATION FILED NOV. 9, 1915.

1,272,348.

Patented July 9, 1918.

UNITED STATES PATENT OFFICE.

NEIL D. CRAWFORD, OF ELIZABETH, NEW JERSEY, ASSIGNOR TO RUBBER REGENERATING COMPANY, A CORPORATION OF INDIANA.

APPARATUS FOR MANUFACTURING ARTICLES FROM LIQUID MATERIAL.

1,272,348.

Specification of Letters Patent.

Patented July 9, 1918.

Application filed November 9, 1915. Serial No. 60,595.

To all whom it may concern:

Be it known that I, NEIL D. CRAWFORD, a citizen of the United States, residing at the city of Elizabeth, county of Union, State 5 of New Jersey, have invented new and useful Improvements in Apparatus for Manufacturing Articles from Liquid Material, of which the following is a full, clear, and complete disclosure.

10 This invention relates to the manufacture of various articles from certain volatile or other liquids by dipping forms into such liquid and afterward allowing the same to dry or harden. The invention relates particularly to the manufacture of rubber articles such as rubber gloves, nipples, etc., in which the forms are successively dipped in a solution of rubber and allowed to dry by evaporation in a suitable atmosphere, or in 15 the presence of a vacuum or partial vacuum.

The object of the present invention is to produce an apparatus in which the dipping and drying operations may be accomplished quickly and efficiently, and in which the 20 volatile constituents of the solution of rubber into which the goods are dipped may be recovered. For a detailed description of one form of my invention reference may be had to the following specification, and 25 to the accompanying drawing forming a part thereof, in which—

Figure 1 is a vertical sectional view of my improved apparatus, certain parts being shown in elevation for the sake of clearness:

Fig. 2 is a transverse sectional view, the right-hand ends of the containers shown in Fig. 1 being removed.

Fig. 3 is a plan view of a detail of the 40 device showing means for limiting the motion of the carriers and forms; and

Fig. 4 is a side elevation partly in section, showing one of the trucks for supporting the forms and the carriers.

45 Referring to the drawing the numeral 1 indicates the floor of a room in which the apparatus is located. Beneath said floor is a pit or well 2 in which is located a hydraulic cylinder 3 carrying a plunger 4. At 50 the bottom of the cylinder is a pipe connection 5 through which fluid under pressure is supplied beneath the plunger 4 and through which said fluid may be allowed to escape. A valve 6 controls the supply 55 and escape of a fluid medium under pres-

sure, to and from the cylinder 3. The plunger 4 carries at its upper end a platform 7 on which are fixed rails 8 adapted to support a wheeled tank 9. The numeral 10 indicates a casing adapted to surround the 60 tank 9 and provided with a movable door 11 through which the tank 9 may be introduced into the casing by rolling it along the rails 8, the floor 1 being also supplied with rails 12 leading up to the casing 10.

65 The interior of the casing 10 is preferably lined with coils of pipe 13, through which brine or other cooling medium may be circulated in order to keep the liquid in the tank at a low temperature thereby preventing too rapid evaporation from its surface. On the casing 10 is mounted a larger casing 14 within which the forms being 70 dipped are contained during the dipping and drying operation. This casing is provided at its ends with suitable doors 15 which allow the introduction of the forms. These doors are designed to fit sufficiently tight to prevent leakage when the interior of the chamber is under a partial vacuum. 75 The upper portion of the chamber is preferably provided with a series of heating coils 16 which raise the temperature of the interior of the chamber so that the evaporation is increased and the drying operation 80 accelerated.

85 The forms are introduced into and operated within the chamber formed by the casing 14 in the following manner:

The numeral 17 indicates a suitable track 90 which forms an extension of exterior tracks 18 and 19, each of which is preferably formed of angle irons as indicated. Numerals 20 and 20' indicate wheeled trucks adapted to run on the rails 17, 18 and 19. These 95 trucks on each side of the device are connected by the shaft 21 which passes through bearings in the said trucks. This shaft where it passes through said bearings is provided with small recesses 22 located diametrically opposite each other and adapted to receive a metallic ball 23, which is forced downwardly by a helical spring 24, the latter being retained in position by a screw plug 25. This arrangement allows the shaft 21 100 to be rotated within the bearings, but in two positions 180° apart the shaft will be held from rotation unless some external force is applied thereto. The shaft 21 supports the carrier or table 26 upon which are 105 110

mounted the form holders 27. One end of the shaft is provided with a head 28 in which is a groove 29, so disposed as to be horizontal when the carrier 26 is in its upper and reversed positions. Projecting through the side of the casing 14 is a short shaft 30 the inner end of which is provided with a rib or flange adapted to fit within the groove 29 in the head 28 carried by either 5 of the trucks 20 or 20'. The shaft 30 carries on its outer end a lever or other suitable handle 31 by which said shaft may be rotated when in engagement with one of the heads 28. It will thus be seen that when 10 a truck is located within the center of a chamber as indicated in dotted lines in Fig. 1 the handle 31 may be turned 180° thereby reversing the carriers 26 from the positions shown at each end of the casing to 15 an inverted position shown in dotted lines.

The following means are provided for moving the trucks 20 and 20' on the rails 17 within the chamber 14: The numerals 32 and 32' indicate arms projecting downwardly from the trucks 20 and 20', respectively, each engaging a series of pins 33 on one of the two belts or sprocket chains 34 located respectively slightly below the rails 17 on opposite sides of the chamber. Each 20 of the chains 34 runs over suitable sprocket wheels 35 and 36, the sprocket wheels 36 being keyed, respectively, to transverse shafts 37 and 37' capable of being rotated by a removable crank 38. Through the medium 25 of this crank the sprocket chains at opposite sides of the chamber are caused to travel in either direction as required. To limit the motion of the trucks 20 toward the center of the chamber I provide two stops. These 30 are shown in the form of two pins 39 and 40 (Fig. 3) adapted to be withdrawn from or inserted into the path of the trucks 20 and 20'.

In order to separate the tank 9 from the 45 interior of the chamber 14 suitable doors are provided as indicated by numerals 41 and 42. These are fixed to transverse shafts 43 and 44, which shafts are provided at their outer ends with suitable handles or cranks 45. Thus when the tank is being put in use the 50 doors 41 and 42 may be raised and placed in a substantially vertical position while the forms are being dipped. When the forms are being removed from the chamber 14 the 55 doors 41 and 42 may be shut thereby isolating the tank 9 and preventing undue evaporation.

The numeral 46 indicates a pipe through which a vacuum may be produced or a suitable drying medium supplied to the dipping chamber.

The operation of dipping and drying is described as follows:

Supposing the chamber 14 to be empty of carriers, one carrier is rolled along the rails

18 on to the rails 17 through the left-hand door 15 (suitable bridge pieces for the rails being provided) until the projection 32 on the truck 20' comes into the path of one set of pins 33 on its corresponding sprocket 70 chain. One of the cranks such as the crank 38 is then rotated so that said pins engage said projection 32 and force the truck 20' along the rails 17 to the opposite or right-hand end of the chamber 14. A second truck 75 20 is then inserted in a similar way but allowed to remain in the left-hand end of the chamber. The downward projecting arm 32 of the second truck must obviously engage the pins on the sprocket chain at the 80 other side of the chamber from the first. After the forms have been inserted the doors 15 are closed and a vacuum or partial vacuum is created within the chamber 14.

A tank containing the solution from 85 which the articles are to be formed having been inserted within the chamber 10, one of the cranks such as 38 is then turned so as to move the truck 20' with the corresponding carrier to the center of the chamber 14 so 90 that the head 28 engages the end of the shaft 30. The lever 31 is turned to the position shown in dotted lines in Fig. 1 thereby reversing the carrier and causing the form holders and forms to be suspended downward. The doors 41 and 42 are then opened and the valve 6 manipulated to raise the platform 7 and tank 9 so that the forms on the carrier immediately above are immersed 95 in the solution in the tank. The tank 9 is 100 then lowered, the carrier immediately above reversed in position and moved with its truck 20' to its original position. The truck 20 is then moved toward the right to the center of the chamber inverted in the same 105 way and the tank 9 raised to dip the goods supported on said carrier. The right-hand carrier is then moved to the center of the tank and the dipping operation repeated. This may be done alternately with each car- 110 rier until the required number of dips are completed after which the trucks and carriers are removed through the right-hand end of the chamber by reversing the operation followed in introducing them.

After the carriers have been removed from the dipping chambers they are inserted in a suitable vulcanizing or curing chamber where the necessary vulcanization of the rubber deposited on the forms is obtained.

In order to economize heat in the dipping chamber, and to prevent condensation on the forms when inserted therein the carriers and forms are preferably first introduced into a preliminary heating chamber 125 and brought to a temperature substantially that maintained in the dipping chamber. It will also be understood that in addition to heating the dipping chamber a vacuum or partial vacuum is maintained therein dur- 130

ing the dipping operation thereby aiding evaporation and allowing the solvent to be collected by subsequent condensation. The use of a vacuum also reduces the amount of moisture within the dipping chamber since a large part of the air which carries the same is removed. The final curing may also be carried out under a vacuum or partial vacuum thereby eliminating entrapped gases 10 and removing moisture.

Having thus described this form of my invention, what I claim and desire to protect by Letters Patent is:

1. In a dipping and drying apparatus, a 15 vacuum chamber, means for controlling a drying medium therein, a chamber for a dipping solution, a horizontal support and a plurality of carriers thereon for forms, a carrier being disposed at each side of said 20 chamber, means for reciprocating each carrier into and out of register with said chamber, and means for relatively moving the carrier and chamber to immerse the forms in the dipping solution.

25 2. In a dipping and drying apparatus, a vacuum container, means for controlling a drying medium therein, a dipping chamber, a horizontal support extending beyond the opposite sides of said chamber, and a carrier for forms disposed on said support at each side of the dipping chamber, each carrier being movable toward the other and into register with said chamber.

3. In a dipping and drying apparatus, a 35 vacuum container, a plurality of carriers for the forms upon which articles are to be made, means for reciprocating said carriers alternately in a rectilinear path within said container and means for dipping the forms 40 at a point intermediate the ends of said path, while said carriers are confined to said path.

4. In a dipping and drying apparatus, a 45 vacuum container, a plurality of carriers for the forms upon which articles are to be made, means for confining the travel of said carriers to a rectilinear path through said container, and means for raising a mass of the material used in the manufacture of 50 said articles, into contact with said forms while said carriers are confined in said path.

5. In a dipping and drying apparatus, a 55 vacuum container, a plurality of carriers for the forms upon which articles are to be made, a horizontal guide-way for said carriers in said containers, and means for raising a mass of the material used in the manufacture of said articles, into contact with said forms while on said guide-way.

6. In a dipping and drying apparatus, a 60 vacuum container, a plurality of carriers for the forms on which articles are to be made, a horizontal guide-way for said carriers in said container and adapted to support two carriers therein, means for moving 65 said carriers alternately to and from the central portion of said container and means for raising a mass of the material, used in the manufacture of said articles, into contact with said forms while on said guide-way.

7. In a dipping and drying apparatus, a 70 vacuum container, a plurality of carriers for the forms on which articles are to be made, means for moving said carriers back 75 and forth through said containers, means for inverting said carriers at the central portion of said container and means for alternately immersing said forms in a mass of the material used in the manufacture of 80 said articles, while said forms are inverted.

8. In a dipping and drying apparatus, a 85 vacuum container, a plurality of carriers for the forms on which articles are to be made, means for moving said carriers back and forth through said container, means for inverting said carriers at the dipping point, and means for raising a mass of the material used in the manufacture of said articles into 90 contact with said forms when said carriers are inverted.

9. In a dipping and drying apparatus, a 95 container, a guide-way therein, trucks adapted to travel on said guide-way, carriers for the forms on which articles are to be made mounted on said trucks, means operated externally of said container for propelling said trucks, and means for inverting said carriers on said trucks at the dipping point.

10. In a dipping and drying apparatus, a 100 container, a guide-way therein, trucks adapted to travel on said guide-way, carriers for the forms on which articles are to be made mounted on said trucks, means operated externally of said container for propelling two trucks therein independently of each other, alternately to the dipping point, means operated externally of said container for inverting said carriers at the dipping 105 point, and means for raising a mass of the material, used in the manufacture of said articles, into contact with said forms when inverted.

Signed at New York, N. Y. this 29th day 110 of October, 1915.

NEIL D. CRAWFORD.
